UNITED STATES PATENT OFFICE.

JOHN H. HANKINSON, OF NEW YORK, N. Y.

DESIGN FOR A COAL GRATE OR BASKET.

SPECIFICATION forming part of Design No. 17,974, dated December 20, 1887.

Application filed October 27, 1887. Serial No. 253,561. Term of patent 7 years.

To all whom it may concern:

Be it known that I, JOHN H. HANKINSON, a citizen of the United States, residing at New York, in the county and State of New York, have invented and produced a new and original Design for Coal Grates or Baskets for Fire-Places, of which the following is a specification, reference being had to the accompanying drawings, forming part thereof.

10 Figure 1 is a perspective view of my newly-designed coal grate or basket, and Fig. 2 is a plan or top view of the same.

The leading features of my design consist in the uniform concavo-convex figure or outline 15 of the sides and ends of the basket between the top and bottom frames, the same being made to represent uniform open netting with raised intersections of vertically-curved and longitudinal ribs when viewed in elevation or 20 perspective, as shown in Fig. 1 of the drawings.

In the drawings, A denotes the grate or basket bottom; B, the rectangular grooved base-frame, supported on legs C. D is the plain

rectangular top frame, mounted with ornamental knobs E. The concavo-convex sides and ends H H are united at the corners to the four curved arms I and to the top and base frames, B and D. At the intersection of the vertically-curved and longitudinal ribs constituting the netting or basket-body the work is raised and presents the appearance of undulating or waved lines.

The entire body of the basket between the base and top frames presents a general contour 35 of curved or undulating lines.

Having described my new design for coal-baskets, I claim—

The design for a coal grate or basket herein shown and described, the same consisting of 40 the concavo-convex sides and ends H H, united to the curved arms I, forming undulating lines within the rectangular base and top frames, B and D.

JOHN H. HANKINSON.
